UNITED STATES PATENT OFFICE.

JOHN JARDINE, OF KINGSWAY, LONDON, ENGLAND.

CRANE AND LIKE HOISTING APPARATUS.

1,368,157.

Specification of Letters Patent.

Patented Feb. 8, 1921.

Application filed December 16, 1920. Serial No. 431,220.

To all whom it may concern:

Be it known that I, JOHN JARDINE, a subject of the King of Great Britain, residing at King's House, Kingsway, in the county 5 of London, England, have invented new and useful Improvements in and Relating to Cranes and like Hoisting Apparatus, of which the following is a specification.

This invention relates to hoisting apparatus in which provision is made for luffing, or derricking, movements and in which devices are employed for causing the suspended load to move in a horizontal, or approximately horizontal, plane, while the jib, 10 or the like, is being raised or lowered, the object of this invention being to obtain the aforesaid result by means which are much simpler than those heretofore employed, or proposed.

20 Such means as hitherto proposed have comprised a pulley over which the hoisting rope, or chain, passed, the said pulley having been proposed to be carried by a trolley movable along the jib, and, in some cases, 25 to be operated by a rope, or chain, passing over other pulleys, one of these being so mounted that it could be caused to approach, or recede from, the other of the said pulleys, the movements of the first named of 30 the said pulleys being controlled and regulated by a toothed wheel, or sector, which could turn with the jib, or the equivalent, about its derricking center.

According to the present invention the 35 rope, or chain, which operates, or controls, the trolley is at one end anchored to, or connected with, a member, carried on, or by, any suitable movable, or stationary part of the apparatus such as the jib, or the super- 40 structure and, at the other end, is connected with, or to, the trolley and at any suitable part between its two ends passes over a member such as a cam, lever, or the equivalent, having such movement relatively to the 45 luffing, or derricking, movement of the jib that the trolley moves along the jib to an extent such as will cause the load to travel in a horizontal, or other predetermined, path when luffing or derricking. The said 50 cam, lever, or the equivalent, mounted, or carried as aforesaid, (directly, or indirectly) either on the jib, or superstructure, or some part in connection with either, is operated by a member movable relatively to the jib 55 which member may be virtually a continuation of the rope operating the trolley.

The accompanying drawing illustrates in a diagrammatic manner a derrick crane provided with what is, I consider the best means for carrying the present invention 60 into effect, but I do not limit myself to these precise means.

Figures 1 and 2 are side elevations respectively showing the jib lowered and raised.

The rope, or chain, 1, which controls the 65 trolley 2, is connected, at its lower end, to the part of the cam, or snail, 3, of smallest radius, the other end of the said rope, or chain, 1, passing over the pulley 4, mounted upon a center-pin 5, at the head of the jib 70 6, and being connected, at 7, to the trolley 2, which can slide up and down in guides 8 in the jib 6. The rope, or chain, 9, by which the jib 6 is raised and lowered is connected at one end to, or to some part in connection 75 with, the head of the jib 6, and at the other end to a pulley, or drum, 10, which is keyed to a shaft 11, to which the cam, or snail, 3, is also keyed. The rope, or chain, 12, by which the load on the hook 13, is raised and 80 lowered, passes over the pulley 2^a, and is wound upon, and unwound from, the winch 14, and is shown as being supported by a roller 15 carried upon the shaft 11.

When the jib 6, is raised upon its center 85 16 on the supporting structure 17, by rotating the shaft 11, and consequently the pulley, or drum, 10, sufficiently, the cam, or snail 3, will correspondingly move through sufficient of a rotation to cause the rope, or chain, 1 90 to unwind from the said cam, or snail, and allow the trolley 2 and pulley 2^a, to descend in the guides 8, on the jib 6, sufficiently to keep the load on the hook 13, in the same, or practically the same, horizontal plane and 95 when the jib 6 is lowered by rotating the pulley or drum 10, in the reverse direction the cam, or snail, 3, will take up a corresponding amount of the rope, or chain 1, to haul up the trolley 2 and pulley 2^a in the 100 guides 8 on the jib 6, to an extent in accordance with that of the descent of the jib 6 to still keep the load on the hook 13 in the same, or practically the same, horizontal plane. 105

Although the cam, or snail, 3, is shown of non-circular form and the pulley, or drum, 10, of circular form, the invention is not limited to this as the varying compensating effect can be obtained by suitably varying the formation of either the said snail, or cam, or the said pulley, or drum, or both of 110

them; or, in some cases, both the said parts may be circular.

It will be understood that the invention is not limited to mounting the parts by which the respective ropes, or chains, are manipulated upon the particular portions of the apparatus illustrated as they can be mounted upon, or carried directly, or indirectly, by, any other convenient portions of either of the supporting structure, or the jib.

In the following claims the expression "chain" includes a rope and the expression "cam" includes a lever, or the equivalent.

15 What I claim is:—

1. In hoisting apparatus, a pivoted jib, a pulley movably supported by the jib, a hoisting cable passing over said pulley, a cable controlling the position of said pulley with respect to the jib, a hoisting mechanism and a cam operated thereby, said pulley-controlling cable directly engaging said cam and being operated thereby to maintain the load at a substantially constant elevation during 25 the rise and fall of the jib.

2. In hoisting apparatus, a pivoted jib, a

trolley slidable thereon, a hoisting cable supported by the trolley, a trolley cable, a jib cable, a winding mechanism for the jib cable, an associated cam directly engaged by the trolley cable, and means for operating said jib cable winding mechanism and the cam device in harmony to maintain the load on the hoisting cable at a substantially constant elevation during the rise and fall of the jib. 30

3. In hoisting apparatus, a pivoted jib, a trolley slidable thereon, a hoisting cable supported by the trolley, a trolley cable, a jib cable, a winding drum for the jib cable, a cam fast on the drum axis and engaged by the trolley cable, and means for rotating the winding drum and cam to lift or lower the jib while maintaining the load on the hoisting cable at a substantially constant elevation. 35

In testimony whereof I have signed my name to this specification in the presence of two subscribing witnesses.

JOHN JARDINE.
